UNITED STATES PATENT OFFICE.

JAMES HENRY PRALL, OF INNES, SASKATCHEWAN, CANADA, ASSIGNOR OF ONE-HALF
TO GEORGE INNES, OF PHILADELPHIA, PENNSYLVANIA.

SHOCKER.

1,341,586.

Specification of Letters Patent. Patented May 25, 1920.

Application filed October 16, 1916. Serial No. 125,864.

To all whom it may concern:

Be it known that I, JAMES H. PRALL, a citizen of the United States, resident of Innes, Province of Saskatchewan, Dominion of Canada, have invented certain new and useful Improvements in Shockers, of which the following is a specification.

The object of my invention is to provide an attachment for a binder, of simple construction and comparatively light draft, which will receive the bundles of grain from the binder in any number desired and when a sufficient number has been collected, deposit them upon the ground in the form of a shock.

A further object is to provide a shock of such construction that the tops of the bundles will be pressed together and the butts separated to such an extent that all danger of the bundles or the shock toppling over when placed upon the ground will be avoided and without the use of twine or other shock binding means.

Other objects of the invention will appear from the following detailed description.

The invention consists generally in various constructions and combinations, all as hereinafter described and particularly pointed out in the claims.

In the accompanying drawings forming part of this specification,

Figure 1 is a plan view of a shocker embodying my invention, the normal position of the shocking basket being shown in full lines and its dumping position in dotted lines.

Fig. 2 is a horizontal sectional view on the line $x-x$ of Fig. 3,

Fig. 3 is a longitudinal sectional view of the same,

Fig. 4 is a sectional view on the line $y-y$ of Fig. 2,

Fig. 5 is a side elevation of the machine, showing the normal position of the bundle receiving pans in full lines and their dumping position in dotted lines,

Figs. 6 and 7 are detail views, showing the position assumed by the parts in delivering the bundles to the pans,

Fig. 8 is a front elevation of the machine,

Figs. 9 and 10 are detail views of the ratchet mechanism forming a part of the bundle delivering attachment of the machine,

Fig. 11 is a detail view of the cable and pulley, through the operation of which the bundle pans are tilted.

In the drawing, 2 represents a side portion of a grain binder of ordinary construction. 3 is a draft connection, secured to the under side of the binder by suitable means, such as U-shaped clamps 4. This draft connection 3 projects laterally beyond the binder and has a pivotal connection at 5 with the forward end of a pole 6 that is connected to a suitable axle 7 and provided with brace rods 8. The axle has carrying wheels 9 and 10, the latter provided with traction pins or studs 11. The draft connection 3 and the pole 6 may be made of any suitable material, metal or wood, as preferred.

The pivotal connection of the shocker with the binder is preferably in line with the axis of the bull and grain wheels, as indicated in Figs. 1, 5 and 8.

The draft connection, as shown in Fig. 2, is preferably V-shaped in form and supports a frame 12 secured thereto. A shaft 13 is mounted in the frame 12 and carries a ratchet wheel 14 having peripheral teeth 15 (see Figs. 4, 9 and 10) and a series of pins 16 mounted in one face opposite and adjacent the shoulders of the teeth 15. An arm 17 is loosely mounted on the shaft 13 and projects upwardly through a slot 18 in the deck 19 of the binder and in the path of one of the kicker arms 20 to be actuated thereby. The arm 17 has a dog 21 that is normally held against the teeth 15 by the tension of a spring 22 and when the arm 17 is struck by the kicker and pushed to the position indicated by dotted lines in Fig. 10, the dog 21 will slide over the teeth of the ratchet and when the arm is disengaged from the kicker the spring 22 will return the arm to its normal position and revolve the ratchet wheel. A shaft 23 is mounted in bearings adjacent to the lower end of the deck and is provided on one end with a division board 24 and on its opposite end with a wing or lug 25 which projects into the path of the pin 16 to be actuated thereby for the purpose of rocking the shaft 23 to raise the division board, as will hereinafter appear.

A standard 26 is mounted on the middle portion of the pole 6 and projects upwardly therefrom and has a bearing at its upper

- end for a shaft 27 having hubs 28 and 29 mounted thereon. (See Figs. 1, 3, 5, and 11.) Arms 30 and 31 are secured at one end respectively in said hubs and project 5 forwardly and downwardly therefrom and support pans 32 and 33 having vertical pivots at 34 on said arms to rock in a horizontal plane, being normally held in alinement with said arms by springs 35. (See Fig. 1.)
- 10 The purpose of having these pans oscillate is to allow them to be alined with the end of the binder deck in position to receive the bundles therefrom, while permitting the rear portion of the shocker to swing inwardly toward the binder or outwardly therefrom, as in turning.

I do not wish to be confined to the number of pans shown herein or the manner of mounting the same, as I may find one pan 20 to be more suitable for the purpose than two, and I may wish to mount the pan to compensate for the adjustment of the binder. In the construction herein shown, I have provided the pan 32, or the one adjacent to the binder deck, with slots 36 to receive projections 37 which are mounted on the deck and extend outwardly therefrom on each side of the opening 18. These 25 extensions receive the bundles and guide the foremost one over the first bundle pan upon the second one. The pans have spurs 37' thereon for engaging the bundles and the pan 32 has points or projections 38 which engage the wild mustard or any weed that 30 may be clinging to the binder and tear it loose. (See Fig. 7.)

I prefer also to provide a guide 69 near the normal position of the pans for engaging the edges thereof and directing them to their normal, receiving position in alinement with the end of the binder deck and against, if necessary, the tension of the 40 springs 35. This function of the guide 69 may follow from the swinging of the shocker frame around toward the binder, as in the act of turning or when the binder and shocker are not in the relative position shown in Fig. 1.

50 The packer arm of the binder is indicated in dotted lines in the figures (6 and 7) and against this arm the grain is packed until a predetermined point is reached, when the packer arm is withdrawn and the kicker operates to discharge the bundle off the deck. The first bundle, as indicated in Fig. 6, 55 slides over the extensions 37 and drops upon the pan 33, the division board 24 then being in its lowered or normal position, as shown in Fig. 5. As soon as the kicker passes out of engagement with the arm 17, the spring 22 will return this arm to its 60 raised position and rock the ratchet wheel 14 and cause one of the pins 16 to engage 65 the wing or lug 25 and rock the shaft 23

sufficiently to raise the division board 24 to the point indicated in Fig. 7, where it will be between the two pans and in the path of the second bundle. The division board will remain in this position while the arm 17 is 70 being moved again by the kicker to the dotted line position shown in Fig. 10, but on the return of the arm 17 after the discharge of the second bundle from the deck, the pin in engagement with the wing 25 will be moved 75 sufficiently to clear this wing and allow the shaft 23 to rock and the division board 24 to swing down to its normal position below the level of the pans. At this time one of the pins 16 will contact with a trip lever 39 mounted at 40 and having a flexible connection 41 around a double pulley 42 (Fig. 2) 80 with a rocking clutch arm 43 which controls the movement of a clutch 44 for temporarily locking a cam 45 on the axle 7. A lever 46 is pivoted at 47 and has one end bearing on the cam 45 and is connected at its other end through a cable 48 with the periphery of a pulley 49 on the shaft 27 for rocking the said shaft and raising the arms 30 and 31 from their normal position, shown in Fig. 1, to an inverted position for discharging the bundles into the shocker basket at the rear of the machine, as indicated in Fig. 5. Instead of operating the trip lever 46 through the movement of the pins 16, I may 90 actuate it from some other moving part of the machine, such as the needle.

The cable 48 has an extension spring 50 therein which is put under tension when the lever 46 is oscillated to tilt the bundle pans to their discharging position to pack the bundles in the shocker basket and also to offer a yielding resistance to the return of the pans to their normal position and prevent them from striking their support with a jar or shock, which might result if the pans were allowed to fall back to their normal receiving position through their own weight. A disk 45' is mounted to revolve with the cam 45 and the clutch arm 43 rides on the edge of this disk and is held thereby in position to keep the clutch members in engagement with one another until the said arm reaches a depression or recess 45'' provided in the edge of said disk, and upon entering this depression a spring 46' will return the clutch arm and clutch connected therewith to their normal, inactive position and allow the bundle pans to remain stationary until they are again filled and the clutch again engaged.

A smaller pulley 51 is mounted on the shaft 27 and a cable 52 is attached thereto and to an extension spring 53 which is put under tension when the pans are tilted from the position shown in full lines in Fig. 5 to the dotted line position in the same figure. When the cam 45 has revolved a sufficient 130

distance to relieve the pressure of the lever 46, the tension of the spring 50 will be relaxed and the spring 53 will then swing the empty pans back to their normal position, the spring 50 exerting sufficient pull on the cable 48 to retard the descent of the pans and cause them to drop gently upon their support in position to receive another pair of bundles from the binder.

10 In the rear of the axle is a frame 54 of suitable material, having shoes 55 which have a hinged connection with the axle through links 56. (See Figs. 2 and 3.) This frame supports the basket to which the 15 bundles are delivered by the tilting pans. The basket normally occupies the raised position indicated in Fig. 5 and is provided with walls 57 having inwardly turned ends 58 at the front of the basket. The side rails 20 54^a of the frame 54 have laterally projecting portions 54^b arranged to telescope in the forward end rail 54^c, as shown in Figs. 1 and 2, to allow the walls of the basket to be adjusted toward or from each other to decrease or increase the width of the basket 25 and its bundle capacity. The frame also has a central rail 59 and an arched rail 60 above it, on which wings 61 are hinged. A sleeve 62 is mounted on the rail 59 and links 63 30 pivotally connect it with the lower portions of the wings 61 to allow the lower edges of the wings to be spread apart and drawn together to adapt them for the varying widths of the basket. The wings are also 35 tapered from their forward toward their rear ends to allow them to be easily withdrawn from the shock when the basket is tilted down to a horizontal position to discharge its contents. The shoes 55, as shown 40 in Figs. 2 and 3, project under the walls of the basket and rest upon the ground when the basket is tilted down to its dumping position. The links 56 at the forward end of the shocker basket have the function of 45 allowing the basket to tilt or ride upwardly at its forward end when it strikes an obstruction, or sway from side to side to clear any obstacle when the basket is in its horizontal discharging position and is being 50 drawn along during such discharge. This manner of mounting the basket I have found to be an important feature of my invention.

A rod 64 connects the forward portion of the basket with one end of a lever 65 which 55 is centrally pivoted at 66 on the standard 26 and the connection of the rod 64 with the lever is normally in advance of the center of the pivot 66 and is held in this position by the tension of a spring 67 which connects the lever 65 with the forward portion 60 of the frame. This rod permits the lateral oscillation or rocking of the basket to accommodate itself to irregularities of the ground over which it may be moving when 65 dropped to its discharging position. The

basket will remain in the position shown in Fig. 5 until the desired number of bundles have been placed therein to form a shock, and at this time the driver of the machine, through the cable 68 attached to the lower 70 end of the lever 65, and passing around the double pulley 42 and from thence to a point in the driver's seat, may tilt this lever on its pivot and allow the basket with the bundles therein to drop down to its horizontal discharging position. The dotted line position of the pans in Fig. 5 indicates the stroke of the pans when the basket is nearly full of bundles. It will be understood, however, that when the first bundles are discharged, the pans will swing down nearer the forward end of the basket and the bundles will be laid in a substantially horizontal position therein, one above another, upon each side of the spreader 61, and as these 80 bundles are laid in the basket, their butt ends will be separated by the spreader a sufficient distance to insure the shock assuming and remaining in an upright position when the basket is filled and dropped down 90 to discharge the shock.

The walls of the basket are so formed, as indicated in Fig. 5, that the first bundles deposited will assume a backwardly and downwardly inclined position therein, the 95 tops of the bundles being pressed together as they are discharged from the pans and the straws of one bundle allowed to intermingle with those of the adjacent bundles, while the butts are spread apart or separated 100 so that when the basket load is deposited upon the ground, the shock will assume and remain in an upright position and the basket may be withdrawn from engagement therewith without danger of the shock or any of 105 the bundles toppling over.

When the basket has discharged its contents, the driver will release the cable 68 and the tension of the spring 67 will return the lever 65 to its normal position and raise 110 the basket to its substantially upright or filling position, ready to receive another supply of bundles from the pans.

The operation of the machine is as follows: The first bundle is delivered upon the 115 bundle pan remote from the deck of the binder, assuming that two pans are used. The division board is then raised and the second bundle delivered to the adjacent pan, and at this time the ratchet mechanism will 120 throw the clutch on the axle and set the mechanism in operation for tilting the bundle pans to an inverted position and discharging the bundles into the raised shocker basket, wherein the bundles will lie, one 125 upon the other, with their heads or tops compressed and interwoven, while the butts will be loose and spread apart. This will follow from the general shape of the walls of the basket and the spreader interposed 130

between the walls, as hereinbefore specifically described. The pans will then be returned to their receiving position and the operation will be repeated until the basket 5 is filled with bundles or until the desired number for a shock has been placed therein. The driver will then trip the basket and drop it to its horizontal discharging position, the butt ends of the bundles will strike 10 upon the ground and, as the machine moves along, the basket will be withdrawn from engagement with the bundles, leaving them in an upright position in the form of a shock and the tops of the bundles being pressed together and the butts loose and spread apart, there will be no danger of the shock falling over when the supporting walls of the basket are withdrawn. The basket filling operation will immediately be resumed and continued until the basket is filled again. 15

I do not wish to be confined in this application to the mechanism shown for controlling the movement of the pans or the shocker basket, or the manner of tripping the mechanism for operating the pans, as in various ways these details of construction may be modified and still be within the scope of my invention.

I claim as my invention:

30 1. The combination, with a binder, of a shocker frame connected therewith, a plurality of bundle pans positioned to receive successive bundles from the binder, the pan remote from the binder receiving the first 35 bundle, means for temporarily separating the remote pan from the adjacent pan, a shocker basket, and means for inverting the bundle pans to deposit the bundles therein.

40 2. The combination, with a binder, of a shocker connected therewith, a bundle pan positioned to receive a bundle from said binder, said pan being mounted for inversion on a horizontal axis, a basket positioned to receive the bundle from said pan when inverted, said pan being also mounted for oscillation on a vertical axis to aline it with the binder deck.

50 3. The combination, with a binder, of a shocker connected therewith, a bundle pan positioned to receive a bundle from said binder, said pan being mounted for inversion on a horizontal axis, a basket positioned to receive the bundle from said pan when inverted, said pan being also mounted for oscillation on a vertical axis to aline it with the binder deck, and a guide mounted in the path of said pan for engaging and alining it on its return to its normal bundle 55 receiving position.

60 4. The combination, with a binder, of a shocker connected therewith, a bundle pan positioned to receive the bundle from the binder, said pan being mounted for inversion on a horizontal axis to discharge the

bundle therein, a basket positioned to receive the bundle from said pan when inverted, and means for alining said pan with the binder deck upon its return to its normal bundle-receiving position. 70

5. The combination, with a binder, of a shocker frame connected therewith, a plurality of bundle pans positioned to receive the bundles from said binder, the remote pan receiving the first bundle, a division 75 board mounted to swing upwardly between the remote and adjacent pans and prevent the second bundle from entering the remote pan, a shocker basket, and means for inverting said pans to deliver the bundles 80 thereto.

6. The combination, with a binder, of a shocker frame connected therewith, bundle pans positioned to receive the bundles from said binder, an arm in the path of the 85 binder kicker, a ratchet mechanism connected with said arm, a division board operated upon the delivery of the first bundle to prevent the over travel of the second bundle, mechanism for tilting said pans to 90 discharge the bundles, a basket whereto the bundles are delivered, and means actuated through the movement of said ratchet mechanism for tripping said bundle pan 95 operating means.

7. The combination, with a binder, of a shocker frame connected therewith, a shocker basket carried thereby, a divided bundle pan positioned to receive bundles from said binder, swinging arms supporting said bundle pan and pivoted substantially midway the shocker frame connection with the binder and the shocker basket; said shocker frame having an axle and carrying wheels therefor, a clutch mounted 100 on said axle, mechanism rendered operative through the movement of said clutch for swinging said arms and bundle pan, and automatically operating mechanism including ratchet mechanism for actuating said 105 clutch to swing the said arms when the bundles are deposited in the pans.

8. A shocker comprising a frame having suitable carrying wheels, a basket hinged to said frame and having a substantially closed forward end, open rear end and substantially open bottom; the side walls of said basket flaring from the top toward the bottom, a spreader carried by said basket and substantially centrally disposed between the 115 side walls thereof; the rear end of said basket being open to allow the discharge of bundles stacked therein, means for maintaining said basket in bundle-receiving position, releasing means therefor to permit the 120 basket to drop to a substantially horizontal position to deposit said bundles with their butts in contact with the ground, and bars arranged to underlie the bundle-receiving 125 spaces of the basket and serve as runners 130

during the period when the bundles constituting the shock are being discharged from the basket.

9. The combination, with a binder, of a shocker connected thereto, a bundle pan positioned to receive a bundle from the binder and mounted for oscillation on a vertical axis for alining the pan with the binder in the different relative positions of the binder and shocker.

10. The combination, with a binder, of a shocker connected thereto, a pair of bundle pans positioned to receive successive bundles from the binder and mounted for oscillation on a vertical axis for alining said pans with the binder to compensate for the different relative positions of the binder and shocker.

11. The combination, with a shocker frame, of a shocker basket pivotally connected therewith, means for holding said basket in a substantially upright position while it is being filled, releasing means therefor to permit said basket to drop down to a substantially horizontal position to discharge its load, and flexible connecting means between the forward portion of said basket and said frame, said connecting means permitting vertical and lateral oscillation of said basket to clear obstructions.

12. The combination, with a shocker frame, of a basket in the rear of said frame, and pivotally mounted links flexibly connecting the forward portion of said basket with the frame; said link connections permitting vertical movement of said basket when in the lowered position to clear obstructions.

13. The combination, with a shocker frame, of a shocker basket, rearwardly extending bars carried by said basket and contacting with the ground when the basket is

tripped to a horizontal dumping position, and pivotally mounted links flexibly connecting the forward portion of said bars with said frame.

14. The combination, with a shocker frame, of a basket, pivotally mounted links flexibly connecting the forward end of said basket to the frame; the latter having a vertical post, a double-ended lever mounted on said vertical post, a rod connecting one end of said lever on one side of its pivot with the forward portion of said basket for holding the latter in a substantially upright position when said lever is in one position, a spring connected to said lever when in this position to resist the downward movement of said basket, and means connected to the other end of said lever on the opposite side of its pivot for rocking said lever and flexing said spring sufficiently to permit said basket to drop to its dumping position.

15. The combination, with a shocker frame, of a basket, pivotally mounted links flexibly connecting its forward end with said frame, a rod having one end pivotally connected with said basket and its opposite end pivotally connected to a movable member for normally holding said basket in an upright loading position, mechanism within control of the operator for moving said rod substantially longitudinally to release said basket and allow it to drop to its dumping position, and means connecting with the dumping mechanism for automatically raising said basket to its loading position when the bundles have been discharged.

In witness whereof I have hereunto set my hand this 9th day of October, 1916.

JAMES HENRY PRALL.
